UNITED STATES PATENT OFFICE.

ISRAEL PUTNAM, OF ELMIRA, NEW YORK, ASSIGNOR TO I. PUTNAM, INC., OF ELMIRA,
NEW YORK, A CORPORATION OF NEW YORK.

TRAP NEST.

Application filed May 20, 1924. Serial No. 714,691.

My present invention relates to poultry raising and more particularly to trap nests and it has for its object to provide a simple, cheap and convenient device of this character that can be easily and quickly set and which will operate with certainty to prevent both ingress and egress when it is once sprung. To these and other ends the invention resides in certain improvements and combinations of parts all as will be herein-after more fully described, the novel features being pointed out in the claims at the end of the specification.

In the drawings:

Figure 1 is a front view of a trap nest constructed in accordance with and illustrating one embodiment of my invention;

Figure 2 is a fragmentary central vertical section therethrough with the door open or in set position;

Figure 3 is a similar view with the door in closed or sprung position;

Figure 4 is an enlarged detail of the door with its locking hinge.

Similar reference numerals throughout the several views indicate the same parts.

It will be obvious from the later description that the nest may be made of wood with metal fittings but I prefer to make the operating parts of sheet metal which makes the nest more compact and easier to ship. To this end I apply to the front of a wooden nest box 1 a metal plate 2 having an opening 3 therein. The lower portion of the front wall of the box may be of wood as indicated at 4 to which portion the lower edge of the front plate is nailed. A narrow vertically sliding plate 5 slotted at 6 is mounted on thumb screws 7 to be adjusted vertically and regulate the size of the opening 3 or rather to vary the height of its lower edge for a purpose that will later appear.

Projecting into the opening 3 from opposite sides thereof near the top are a pair of ears 8 struck from the sheet metal and forming short flat trunnions. The door 9 is supported on these and is shorter than the opening though fitting it fairly closely at the sides. It is preferably made of a sheet metal plate having a hook shaped tongue 10 struck out from its center to provide a hand hold by means of which it may be manipulated as hereinabove described. At each side of the door near its top is an outwardly or forwardly turned preferably triangular

flange or ear 11. This is provided with a vertical slot 12 in each instance which, when the door 9 is closed as in Figure 3, receives the trunnion 8 and holds the door against pivotal or tilting motion, in fact holds it 60 against any movement except an upward sliding movement in a vertical plane.

In this position, the door is at its lowermost point and leaves quite a space 13 of the opening 3 above it which is useful for ventilating purposes. The lower end of the slot 12 communicates with a triangular opening 14 in the ear 11 in the upper angle of which opening is a shoulder 15 adjacent to the point at which the opening merges into 70 the slot. The opening is of such dimensions that the door may be turned to an angular position when the trunnion 8 occupies the opening. To open the door and set the trap nest the door is raised vertically 75 so that the trunnions 8 pass from the slot 12 into the opening 14. The door is then tilted inwardly and the shoulder 15 engaged over the top edge of the trunnion as shown in Figure 2, said trunnion being then disposed against the adjacent side 16 of the opening 14 and its lower edge occupying the forward angle of said opening so that the weight of the door will not dislodge the shoulder.

When the bird enters the nest, the dimensions are such that her back collides with the lower edge of the open door raising it slightly and rotating it in a clockwise direction on a center defined by the contact of the lower edge of the lug 8 with a forward angle of the opening 14. This dislodges the shoulder 15 and the door drops slightly and then rotates by gravity in a counter clockwise direction to its closed position. The trunnions 8, during this process, move into the lower ends of the slots 12 and finally resume their locked positions at the upper ends of the slots 12 as shown in Figure 3 so that the nest is secure against both ingress and egress.

An advantage of having the adjustable sill piece 5 at the bottom of the opening 3 is that the bird usually steps on the sill in entering the nest and in order to assure the proper contact with the door to trip it the said sill piece is regulated according to the size of the bird frequenting that particular nest.

I claim as my invention:

1. In a trap nest, the combination with a

- casing having an entrance opening, of a door therefor adapted to swing in a direction transverse to the plane of the opening and supports for the door rigid upon the 5 casing and adapted for automatically locking the door against opening movement in both directions when it is once moved to closed position.
2. In a trap nest, the combination with a 10 casing having an entrance opening, of a door therefor, supports for the door upon which the latter is adapted to swing and upon which it is also adapted to slide vertically when in closed position, and means for preventing the door from swinging in either direction when it is in its lowermost sliding position.
3. In a trap nest, the combination with a 15 casing having an entrance opening, provided with inwardly projecting trunnions, of a swinging door for the opening having a shoulder adapted to support it in an open position by engaging with the trunnions, and further provided with means for locking the door against swinging movement when the shoulder is disengaged and the door swung to a closed position.
4. In a trap nest, the combination with a 20 casing having an entrance opening provided with an inwardly projecting trunnions, of a swinging door for the opening having a shoulder adapted to support it in an open position by engaging with the trunnions, and further provided with a slot adjacent 25 the shoulder adapted to receive the trunnions and lock the door against further swinging movement when the shoulder is disengaged and the door has once swung to a closed position.
5. In a trap nest, the combination with a 30 casing having an entrance opening provided with inwardly projecting trunnions, of a swinging door for the opening having shoulder means adapted to support it in an 35 inwardly inclined open position by engaging with the trunnions said door when opened being adapted to be engaged by the back of a bird entering the nest to dislodge said shoulder means, and a slot adjacent to 40 the shoulder means adapted to receive the trunnions and lock the door against fur-

ther swinging movement once the shoulder means is dislodged and the door drops to closed position.

6. In a trap nest, the combination with a 55 casing having an entrance opening provided with inwardly projecting flat trunnions, of a swinging door for the opening having lateral ears provided with openings in which the door pivots on the trunnions between 60 open and closed position and with communicating slots and with shoulders adjacent to the slots, the latter being adapted to engage the trunnions and support the door in an inwardly inclined open position, and being 65 further adapted to be dislodged by contact by a bird with the door, the trunnions being adapted to be received within the slot through a vertical movement of the door after it has reached the closed position to 70 thereafter lock the door against swinging movement in either direction.

7. In a trap nest, the combination with a 75 casing having an entrance opening and a door adapted to swing in the opening between 80 open and closed positions, of pivotal supporting devices for the door provided with means tripped by a lifting action on the door for supporting it in an inwardly inclined open position, and means for adjusting the height of the bottom edge of the opening.

8. In a trap nest the combination with a 85 casing having an entrance opening and a door adapted to swing in the opening between 90 open and closed position and to also move vertically in its own plane when in closed position, of pivotal supporting devices for the door provided with means for supporting it in open position and for locking it against swinging movement through the said vertical movement of the door when the latter is in closed position.

9. In a trap nest, the combination of a 95 casing having an entrance opening, supports upon the casing, and a door for the opening carried by and adapted to swing on the supports and being adjustable thereon to open position and arranged to be locked thereby when in closed position.

ISRAEL PUTNAM.
